Primary Examiner — Keli L Hill*Assistant Examiner* — Sara S Sahneh(74) *Attorney, Agent, or Firm* — Mandelbaum Silfin Economou LLP**CLAIM**

The ornamental design for a chair, as shown and described.

DESCRIPTION

FIG. 1 is a perspective view of a chair showing our new design;

FIG. 2 is a front view of the chair shown in FIG. 1;

FIG. 3 is a back view of the chair shown in FIG. 1;

FIG. 4 is a left view of the chair shown in FIG. 1;

FIG. 5 is a right view of the chair shown in FIG. 1;

FIG. 6 is a top view of the chair shown in FIG. 1; and,

FIG. 7 is a bottom view of the chair shown in FIG. 1.

The broken line showing of the chair is for the purpose of illustrating portions of the chair and forms no part of the claimed design.
